UNITED STATES PATENT OFFICE.

ALBIN WARTH, OF STAPLETON, NEW YORK.

MECHANICAL MOVEMENT.

SPECIFICATION forming part of Letters Patent No. 444,283, dated January 6, 1891.

Application filed September 4, 1890. Serial No. 363,882. (No model.)

To all whom it may concern:

Be it known that I, ALBIN WARTH, a citizen of the United States, residing at Stapleton, in the county of Richmond and State of New York, have invented new and useful Improvements in Mechanical Movements, of which the following is a specification.

This invention relates to certain improvements in that class of mechanical movements which are described in Letters Patent No. 151,457, granted to me May 26, 1874; and the improvements which form the subject-matter of my present application for a patent are pointed out in the following specification and claims, and illustrated in the accompanying drawings, in which—

Figure 1 is a plan or top view. Fig. 2 is a front elevation. Fig. 3 is a transverse vertical section in the plane $\alpha\alpha$, Fig. 1. Fig. 4 is a partial vertical section in the plane yy , Fig. 1, on a larger scale than the previous figures. Fig. 5 is a similar section in the plane zz , Figs. 1 and 6. Fig. 6 is a similar section in the plane $z'z'$, Figs. 3 and 5. Fig. 7 is a face view of the carriage detached. Fig. 8 is a sectional view on a large scale, showing a cutting-tool as may be used in connection with my invention.

In the drawings, the letters $A A'$ designate two tables, and B is a guide or rail, which is situated between the two tables, and which may be fastened to one of said tables or to the floor or to the walls, according to circumstances. On this rail is placed a carriage D , which is by preference provided with two pairs of wheels $a a'$, engaging the rail from opposite sides, and which is retained in an upright position by means of a rod b , on which are mounted two wheels $c c'$, which bear on the opposite sides of a rail c^o , Figs. 2 and 3, running parallel with the rail B . The wheels $c c'$ are mounted in a bracket c' , which is secured to the rod b , and from which extends a slotted arm c^o , which straddles the rail d and is provided with a set-screw c^o . If this set-screw is screwed up tight, the carriage D is retained in position upon the rail B ; but if said screw is turned back the carriage can move on the rail B from one end to the other.

In the carriage D is firmly mounted a stud d , (best seen in Fig. 4,) on which is loosely

mounted a two-speed pulley $d' d^o$, and on the driving-shaft E is firmly mounted a pulley e , round which extends a belt F , which runs over a guide-pulley f , the speed d' , the guide-pulley f' , thence down beneath the pulley f^o and over the pulley f^o , thence beneath the speed d' , and over the guide-pulley f^o back to the driving-pulley e . The pulleys f and f' are mounted on brackets f^o and f^{o0} , respectively, (best seen in Fig. 2,) which are secured on a fixed rod or post f^o by means of set-screws, so that they can be adjusted in order to increase or decrease the tension of the belt F . In the same manner the pulleys f^o and f^o are mounted in brackets f^{o0} and f^{o0} , which are secured to a fixed rod or post f^o by means of set-screws, so that by adjusting these brackets the tension of the belt F can be regulated.

On the stud d near its outer end is mounted a bracket g , which carries a dog g' , and between the bracket g and the pulley d' is situated a bar g^o , which turns freely upon the stud d and is provided in one of its edges with ratchet-teeth g^o (see Figs. 2 and 7) in a position to enable the dog g' to engage with them. Said bar g^o carries two pulleys $g^o g^o$, which, when the bar is turned upon the stud, act upon the belt F in such a manner that the pulley g^o depresses the upper branch of said belt upon the pulley d' , while the pulley g^o forces the lower branch of said belt up against the pulley d' , and since the bar g can be adjusted by means of the dog g' the action of the belt F upon the pulley d' can be regulated as may be desired. From this description it will be seen that the carriage D can be moved from one end of the rail B to the other without throwing the pulley d' out of engagement with the belt F , and at the same time a revolving motion is imparted to the pulley d' as long as said belt is in motion.

On the carriage D is formed or secured a platform d^o , (best seen in Fig. 4,) which is provided with a tubular projection d^o , engaging an arm H , which I shall designate hereafter as the "supporting-arm." This arm is fastened on the platform d^o by means of a screw-bolt d^o , and if the nut of this screw-bolt is loose the supporting-arm is free to swing on the tubular projection d^o ; but it can be locked in position by means of a latch h ,

which is attached to it by a set-screw h' , and which, when depressed, engages a recess in the platform d^2 .

On the inner end of the supporting-arm II 5 is mounted the balance-arm I, the connection being such that said balance-arm can freely swing both in a horizontal and also in a vertical plane. Said connection consists of a plate h^2 , which is firmly secured to the supporting-arm II, and upon which is placed a bracket h^3 , provided with two lugs $h^4 h^4$, (best seen in Fig. 6,) and with a tubular projection h^5 , which forms the bearing for an arbor h^6 , on which are mounted two pulleys $h^7 h^8$, which 10 are firmly connected to each other. The balance-arm I rests upon a plate i , which is provided with downwardly-projecting lugs $i' i'$, and is connected to the bracket h^3 by pivots $i^2 i^2$, which extend through the lugs h^4 and i' 15 and both the balance-arm I and the plate i are provided with slots $i^1 i^1$, respectively, which engage the tubular projections h^5 of the bracket h^3 . The plate i is made to extend in the direction of the length of the balance-arm, (see Fig. 5,) and from this extension rise lugs i^3 , which engage the slot i^1 , so as to steady 20 the balance-arm. A screw-bolt i^6 serves to fasten the balance-arm upon the plate i in the desired position.

30 On the balance-arm at or near one of its ends is secured a weight J, and on its opposite end is attached a tool K, which may be a device for cutting cloth, or a grinding-wheel, or any tool which does its work while in motion over different parts of the articles to be acted upon. On the balance-arm is also mounted a shaft L, which is geared together with the tool K. On the shaft L is mounted a pulley l, which connects by a belt l' with the pulley h^5 , Figs. 3 and 6, mounted on the arbor h^6 . Motion is transmitted to this arbor from the pulley d^2 , which is loosely mounted on the stud d in the carriage D, Fig. 4, and firmly connected to the pulley d' , to which motion is 35 imparted by the driving-belt F, as above explained. Over the pulley d^2 extends a belt M, which passes down under two pulleys m m, secured to the rod b, Fig. 2, thence up over two pulleys m' m', mounted on the opposite sides 40 of the supporting-arm II, and thence around the pulley h^8 , mounted on the arbor h^6 . It will be readily seen from this description that the weight J forms a balance for the tool G, and by adjusting the balance-arm in the direction 45 of its length by means of the slot i^1 and screw-bolt i^6 the pressure exerted by the tool upon the table or upon the work over which it moves can be adjusted. At the same time by connecting the balance-arm I to the supporting-arm II, I am enabled to move the tool over a table of considerable width with a comparatively short balance-arm, and when the tool is moved over the table that end of the balance-arm which supports the weight J does not 50 swing beyond the edge of the table, so that it will not interfere with the work of persons engaged near said table. Furthermore, by con-

necting the supporting-arm II to the carriage D, I am enabled to move the tool over every part of the table without throwing the same 70 out of gear with the driving-shaft E.

If it is desirable to use the tool while the carriage D is held stationary, said carriage can be moved over the rail B into the desired position and fastened by means of the set-screw c³, Fig. 1, without throwing the pulley d' 75 out of gear with the driving-shaft, and in that case the nut of the screw-bolt d⁵ is loosened, so that the supporting-arm II can swing on the tubular projection d¹ and the tool can be 80 carried over a large portion of the table or of the work on which it is to act, while the pressure of the tool upon the work is counteracted by the balance-arm. The range of the tool over the work 2 can be still further increased 85 when the screw-bolt i⁶ is released, so that the balance-arm can slide in the direction of its length. It must also be remarked that the weight J may be made integral with the balance-arm without departing from my invention; but I prefer to make the weight J detachable from the balance-arm, so that it can 90 be adjusted on the same, as may be desirable.

The tool which I have shown in the drawings is a knife for cutting out garments such 95 as shown and described in Letters Patent Nos. 380,962 and 380,963, granted to me April 10, 1888, and a reciprocating motion is imparted to this knife from the shaft L by means of a pitman I', Figs. 1 and 8. This pitman engages a crank 8, formed on the shaft L, and it connects with a bell-crank lever 9, which engages a sleeve 10, fitted upon a pillar 12 and engaging lugs 13, which project from the bar of the knife 14. A tool may, however, be 100 used which requires a revolving motion, and the devices for transmitting such motion to the tool from the shaft L will readily suggest themselves to any ordinary machinist.

I do not claim in this application anything 105 claimed in my applications, Serial Nos. 363,883 and 363,884, bearing even date with this.

What I claim as new, and desire to secure by Letters Patent, is—

1. The combination of a fixed guide or rail 110 B, a traveling carriage D, fitted on said guide, a pulley d', mounted on said carriage and geared with a driving-shaft E, an arm II, mounted on the carriage, an arbor h⁶, mounted in said arm and geared with the pulley d², an 115 arm I, connected to the arm II and free to swing both in a horizontal and in a vertical plane, and a tool secured to the arm I and geared with the arbor h⁶, substantially as described.

2. The combination of a fixed guide or rail 120 B, a traveling carriage D, fitted on said guide, a pulley d', mounted on said carriage, the driving-pulley e, the belt F, extending from 125 said driving-pulley over the guide-pulleys f' f³ f⁴, the swivel-bar g², the pulleys g⁴ g⁵, mounted in said swivel-bar and constructed to act upon the belt E, the dog g', for locking the swivel-bar g² in the required position, an

arm H, mounted on the carriage, an arbor h^6 , mounted in said arm and geared with the pulley d' , an arm I, connected to the arm H and free to swing both in a horizontal and in a vertical plane, and a tool secured to the arm I and geared with the arbor h^6 , substantially as described.

3. The combination of a fixed guide or rail B, a traveling carriage D, fitted on said rail, 10 a pulley d' , mounted on said carriage, an arbor h^6 , mounted in said arm and geared with the pulley d' , an arm I, connected to the arm H and free to swing both in a horizontal and in a vertical plane, a tool secured to the arm I 15 and geared with the arbor h^6 , and means, substantially as described, for retaining the carriage D on the rail B in any desired position.

4. The combination of a fixed guide or rail B, a traveling carriage D, fitted on said guide, 20 a pulley d' , mounted on said carriage and geared with the driving-shaft E, an arm H, mounted on the carriage, an arbor h^6 , mounted in said arm and geared with the pulley d' , a balance-arm I, connected to the arm H and 25 free to swing both in a horizontal and in a vertical plane, a weight J, secured to this balance-arm on one side of its fulcrum, and a tool secured to said balance-arm on the opposite side of its fulcrum and geared with the arbor h^6 , substantially as described.

5. The combination of a fixed guide or rail B, a traveling carriage D, fitted on said guide, a pulley d' , mounted on said carriage and geared with the driving-shaft E, an arm H, 30 mounted on said carriage, an arbor h^6 , mounted in said arm and geared with the pulley d' , a balance-arm I, connected to the arm H and free to swing both in a horizontal and in a vertical plane, means, substantially as de- 35 scribed, for adjusting the balance-arm in the direction of its length, a weight J, secured to said balance-arm on one side of its fulcrum,

and a tool attached to the balance-arm on the opposite side of its fulcrum and geared with the arbor h^6 , substantially as described. 45

6. The combination of a fixed guide or rail, a traveling carriage D, fitted on said guide and geared with the driving-shaft E, a balance-arm I, connected to the traveling carriage and free to swing both in a horizontal 50 and in a vertical plane, and a tool secured to the balance-arm and geared with the carriage, substantially as described.

7. The combination of a fixed guide or rail, a traveling carriage D, fitted on said guide 55 and geared with the driving-shaft E, a supporting-arm H, connected to the carriage, a balance-arm I, connected to the supporting-arm and free to swing both in a horizontal and in a vertical plane, and a tool secured to 60 the balance-arm and geared with the carriage, substantially as described.

8. The combination, with the driving-shaft E and the supporting-arm H, of a balance-arm I, attached to the supporting-arm at a 65 point between its ends and free to swing both in a horizontal and in a vertical plane, and a tool secured to the balance-arm and geared with the driving-shaft, substantially as de- 70 scribed.

9. The combination, with the driving-shaft E and the supporting-arm H, of a longitudinally-slidable balance-arm I, free to swing both in a horizontal and in a vertical plane, and of a tool secured to the balance-arm and geared with the driving-shaft, substantially as de- 75 scribed.

In testimony whereof I have hereunto set my hand in the presence of two subscribing witnesses.

ALBIN WARTH.
